UNITED STATES PATENT OFFICE.

JOE JEMELKA, OF MOULTON, TEXAS.

CULTIVATOR.

Application filed December 22, 1921. Serial No. 524,074.

To all whom it may concern:

Be it known that I, JOE JEMELKA, a citizen of the United States of America, residing at Moulton, in the county of Lavaca 5 and State of Texas, have invented certain new and useful Improvements in Cultivators, of which the following is a specification.

This invention relates to certain new and 10 useful improvements in cultivators and has particular reference to an adjustable cultivator plow.

The primary object of the invention resides in the provision of a cultivator having 15 a plow longitudinally adjustable with respect to the mounting beam and also capable of vertical lateral and angular adjustments to vary the position of the cultivator plow point.

20 A further object of the invention has reference to a cultivator wherein the plow member is vertically adjustable with relation to the mounting therefor with the mounting embodying independently operating members for adjusting the angularity and lateral positions of the plow point.

With these general objects in view and others that will appear as the nature of the invention is better understood, the same 30 consists of the novel form, combination and arrangement of parts hereinafter more fully described, shown in the accompanying drawing and claimed.

In the drawing, wherein like reference 35 characters designate corresponding parts throughout the several views,

Figure 1 is a front elevational view, partially in section of a cultivator plow and mounting constructed in accordance with 40 the present invention,

Figure 2 is a fragmentary side elevational view, partly in section,

Figure 3 is a top plan view showing the means for changing the lateral position of 45 the plow and the means for varying the angularity of the plow,

Figure 4 is a horizontal sectional view taken on line IV—IV of Fig. 1 showing the pivotal connection between the plow support and mounting, and the nut for vertically adjusting the plow, and

Figure 5 is an elevational view of the bracket for supporting the plow.

Referring more in detail to the accompanying drawing there is illustrated a frame bar or beam 1 of a cultivator frame

adapted to support a cultivator plow through the medium of a perpendicular bracket plate 2 fixed to an arm associated with the beam 1. A mounting for the 60 bracket plate 2 includes a tubular bearing 3 surrounded by a sleeve 4 having a reduced end 5 for receiving a rigidly mounted laterally directed arm 6. The bracket plate 2 carries an angularly directed side arm 7 65 having a side opening slot 8 in the outer end thereof, the bracket plate 2 being provided with an opening 9 adjacent the lower end thereof to be received on the shouldered end 5 of the sleeve 4, a lock screw bolt 10 70 carried by the outer end of the arm 6 receiving the slotted end 8 of the bracket plate arm 7 for rigidly connecting the arms 6 and 7 together. A locking bolt 11 extending through the tubular bearing 3 carries 75 a washer 12 for securing the sleeve 4 in proper position upon the bearing 3. Shackle bolts 12' enclose the sleeve 4 as shown in Fig. 1 and are associated with strap bearings 13 arranged at opposite sides 80 of the beam 1 for rigidly mounting the bracket plate 2 and its support upon the beam.

The supporting means for the plow point embodies a perpendicular plate 14 85 flatly engaging the outer face of the bracket plate 2, the same being pivotally supported on the bolt 11 as shown in Fig. 4 and constituting an integral part of the tubular bearing 3. To pivotally move the plate 14 and bearing 3 upon the bolt 11, a screw block 15 is secured to the upper end 90 of the plate 14 and extends rearwardly through the slotted opening 16 in the upper end of the bracket plate 2, the bracket plate, adjacent the ends of the slotted opening being provided with brackets 17 constituting journal bearings for the ends of the screw 18 that is associated with the screw block 15, the screw 18 being provided with a 100 crank handle 19 for rotating the same and shifting the screw block in opposite directions, thereby causing a pivotal movement of the perpendicular plate 14.

The direct mounting for the cultivator plow includes outwardly directed arms 20 and 21 carried by the plate 14 and respectively positioned below and above the pivot point of the plate, an adjusting nut 22 being positioned between the arms 20 and 21 and carrying a sectional operating ring 23 to facilitate manipulation thereof. The culti-

vator plow embodies a point 24 carried by a screw standard 25 that projects through the arms 20 and 21 and upon which the nut 22 is threaded.

5 To vertically adjust the plow 24 and to prevent rotation thereof, the screw standard 25 of the plow is provided with opposite side grooves 26 while a disk nut 27 resting upon the upper arm 21 carries inwardly directed keys 28 extending into the shaft groove, the disk nut 27 being retained in position by the overhanging end 21' of the arm 21 as clearly shown in Figs. 1 and 3. To rotate the shaft standard of the plow point 24, the disk nut 27 carries a side extension 29 slotted at its outer end as shown in Figs. 1 and 3 and into which slotted end the pin 30 of the screw block 31 extends, the screw block being supported on the screw 32 journaled at its ends in brackets 33 carried by the plate 14 while the crank handle 34 upon the screw 32 permits operation thereof.

Assuming that the screw standard 25 of the plow is in a perpendicular position, and it being desired to vary the angularity thereof, the screw shaft 18 is rotated in the desired direction causing a pivotal movement of the plate 14 carrying the plow shaft 30 for moving the same either forwardly or rearwardly. When it is desired to vary the height of the plow with respect to the beam 1, the nut 22 is rotated in the desired direction through the medium of the ring 23, the standard 25 being raised or lowered and prevented from rotation with respect to the nut 22 by the disk nut 27 and the screw block 31.

40 To rotate the standard of the plow point 24, the screw 32 is rotated in the desired direction, causing movement of the disk nut 27 which correspondingly rotates the plow standard 25.

45 From the above detail description of the device it is believed that the construction and operation thereof will at once be apparent, and while there is herein shown and described the preferred embodiment of the present invention it is nevertheless to be understood that minor changes may be made therein without departing from the spirit and scope thereof.

50 What is claimed as new is:—

1. Adjustable mechanism for a cultivator plow shaft including a bracket plate fixed to a cultivator frame bar, a perpendicular plate pivotally associated with the bracket plate, manually operable means for pivotally moving said plate, said means comprising laterally extending spaced bearing members carried by the upper end of said bracket plate, the said bracket plate having a transverse slot positioned between said bearing members, a screw having an operating handle journaled in said bearing mem-

bers, and a screw block pivotally carried by said perpendicular plate and extending through the transverse slot for engaging said screw to pivotally move said perpendicular plate, spaced lateral arms carried by 70 said plate, a cultivator standard extending through said arms, an adjusting nut on said standard positioned between said arms for vertically shifting the same, cooperating means carried by said standard and plate 75 to prevent rotation of the standard during vertical adjustment, said cooperating means including a disk nut interlocked with said standard, and a block and screw for shifting the disk nut for rotating the standard to 80 change the position of the plow point.

2. Adjustable mechanism for a cultivator standard including a bracket plate fixed to a cultivator frame bar, a perpendicular plate 85 pivotally associated with the bracket plate, manually operable means for pivotally moving said plate, spaced lateral arms carried by said plate, a cultivator standard extending through said arms, an adjusting nut on said standard positioned between said arms 90 for vertically shifting the same, cooperating means carried by said standard and plate to prevent the rotation of the standard during vertical adjustment, said cooperating means including a disk nut interlocked with 95 said standard and mounted upon one of said spaced lateral arms to be held against displacement thereby, a lateral extension carried by said disk nut, said extension having a slotted end, a pair of laterally extending 100 spaced bearing members carried by the perpendicular plate and positioned above said lateral arms, a screw having an operating handle journaled in said bearing members, and a screw block operatively carried by 105 said screw, said block having a depending pin adapted for engaging the slotted end of said disk nut for shifting the said nut for changing the position of the plow point.

3. Adjustable mechanism for a cultivator standard including a bracket plate fixed to a cultivator frame bar, a perpendicular plate pivotally associated with the bracket plate, manually operable means for pivotally moving said plate, said means comprising laterally extending spaced bearing members carried by the upper end of said bracket plate, the said bracket plate having a transverse slot positioned between said bearing members, a screw having an operating handle journaled in said bearing members, and a screw block pivotally carried by said perpendicular plate and extending through the transverse slot for engaging said screw to pivotally move said perpendicular plate, spaced lateral arms carried by said plate, a cultivator standard extending through said arms, an adjusting nut on said standard positioned between said arms for vertically shifting the same, cooperating means carried by 120 said standard 125 130

standard and plate to prevent rotation of the standard during vertical adjustment, said cooperating means including a disk nut interlocked with said standard and mounted upon one of said spaced lateral arms to be held against displacement thereby, a lateral extension having a slotted end carried by said disk nut, a pair of laterally extending spaced bearing members carried by the perpendicular plate and positioned above said spaced lateral arms, a screw having an operating handle journaled in said bearing members, and a screw block operatively carried by said screw, said block having a depending pin adapted for engaging the slotted end of said disk nut for shifting the said nut for changing the position of the plow point. 15

In testimony whereof I affix my signature.
JOE JEMELKA.
